UNITED STATES PATENT OFFICE

99,021

DESIGN FOR A PORTABLE FIELD KITCHEN

Russell N. Hanson, Albert Lea, Minn.

Application January 27, 1936, Serial No. 60,823

Term of patent 7 years

To all whom it may concern:

Be it known that I, Russell N. Hanson, a citizen of the United States, residing at Albert Lea, in the county of Freeborn and State of Minnesota, have invented a new, original, and ornamental Design for a Portable Field Kitchen, of which the following is a specification, reference being had to the accompanying drawing, forming part thereof, wherein:

Fig. 1 is a top plan view of a portable field kitchen showing my new design;

Fig. 2 is a view in front elevation of the same;
Fig. 3 is a view in rear elevation of the same;
and

Fig. 4 is a view in end elevation of the same.

I claim:

The ornamental design for a portable field kitchen, substantially as shown.

RUSSELL N. HANSON.
